FLASH LAMP

Lester F. Anderson, East Orange, N. J., assignor
to Wabash Appliance Corporation, Brooklyn,
N. Y., a corporation of New York

Application December 3, 1938, Serial No. 243,727

1 Claim. (Cl. 67—31)

This invention relates to new and useful improvements in flash lamps such as are used in photography.

The object of the present invention is to provide a lamp particularly suited for taking photographs with cameras having focal plane shutters. Flash lamps of the prior art, depending whether they were filled with foil or wire, had a more or less highly peaked flash characteristic, and the duration of this flash above the level of photographic effectiveness was not wide enough to obtain complete exposure during the one-fifteenth to one-twentieth of a second timing of the shutter. Attempts to secure this condition by slowing down the burning time of the material in the flash lamp bulb, would unfavorably react on the proper timing of the flash lamp with the shutter.

In accordance with the present invention a plateau type of ignition curve is insured for the flash lamp. This is accomplished by placing the igniting wire well out of the center of the mass of combustible material, the ignition of which supplies the required flash ignition. The time required for igniting is further prolonged by propagating the flash from the priming material predominantly in the directions away from the larger mass of combustible material.

In order more clearly to illustrate the invention I have shown in Fig. 1 in side elevation a flash lamp embodying my invention, and in

Fig. 2 curves comparing the functioning of my lamp with those of the prior art.

As shown in Fig. 1, a glass lamp bulb 1 contains a mass of combustible material, preferably wire of a suitable composition. The wire may be ignited by means of a tungsten filament 3 supported on leading-in wires 4 sealed into stem 5 of the lamp. The wire 3 is located considerably

below the center of the mass of combustible material 2 near the neck portion of the bulb. This relationship is enhanced by compacting the material near the periphery of the spherical portion 5 of the bulb and packing it more loosely in the center of the spherical portion.

The usual primer paste consisting of a mixture of mutually reactive elements or compounds applied to the wire 3 and the supporting ends of 10 the leads by dipping it in the paste before assembly. When assembled in the lamp the paste will collect in a bead on top of the wire 3 and near the tops of the leads 4. The lower portion of this primer paste will not harden to the same extent as the upper portion, and ignition will spread more rapidly downwards (in the direction of the stem) than upwards.

Lamps constructed as illustrated in Fig. 1 have a characteristic curve like 10 shown in Fig. 2. The width of the plateau of this curve is about 50 milliseconds and reaches 1½ and 2 million lumens. Curve 11 illustrates the usual foil type flash lamp which, while it reaches over 5 million lumens is very narrow. 12 illustrates the usual wire-filled flash lamp which is flatter than 11 but the width of which is insufficient. The irregularities in the top of the curve 10 are caused by the density of the filling.

What is claimed is:

30 In a flash lamp a glass bulb closed to the atmosphere and having a spherical portion, combustible wire distributed with substantially uniform looseness throughout the spherical portion except near the periphery where it is relatively compacted, and igniting means in the bulb near the periphery of the sphere embedded in the wire filling but out of the center of the mass of wire.
